UNITED STATES PATENT OFFICE.

HENRY F. REED, OF NEW YORK, N. Y.

DESIGN FOR A FOUNDATION-FRAME FOR A FLORAL ORNAMENT.

SPECIFICATION forming part of Design No. 14,620, dated February 5, 1884.

Application filed December 10, 1883. Term of patent 7 years.

To all whom it may concern:

Be it known that I, HENRY F. REED, of the city, county, and State of New York, have invented and produced a new and original Design 5 for a Foundation for a Floral Ornament; and I do hereby declare that the following is a full and exact description thereof, reference being had to the accompanying drawing, and to the letters of reference marked thereon, making a 10 part of this specification.

The accompanying drawing is a perspective view of my newly-designed foundation for holding flowers to represent a horseshoe-magnet and its armature.

15 The leading feature of my design is a horseshoe-magnet. A represents this feature of the design, the magnet being delineated by an open-work frame in skeleton outlines of the conventional form of an ordinary horseshoe-

magnet. B represents a cross-bar or armature for the magnet, placed in close proximity to the poles or ends of its arms transversely thereto, said armature being likewise delineated in outline by an open-work frame. 20

I claim—

25 The design for a foundation-frame for an ornamental floral piece, the same consisting of the conventional form of a horseshoe-magnet, A, in open-work, having a rectangular open-work bar, B, placed in position across its ends, as 30 shown.

In testimony whereof I have signed my name to this specification in the presence of two subscribing witnesses.

HENRY F. REED.
